MAGNETIC MEMORY EMPLOYING STRESS WAVE
 Rabah Shahbender, Princeton, N.J., assignor to Radio Corporation of America, a corporation of Delaware

Filed Sept. 4, 1964, Ser. No. 394,545
 13 Claims. (Cl. 340—174)

This invention relates to information storage systems, and particularly to memories in which access to storage locations is accomplished by means of a stress wave propagated through magnetic material.

When a magnetic element is subjected to a mechanical stress, the hysteresis loop characteristics of the material change. For example, the corrective H_c necessary to switch the direction of magnetization in the magnetic material is changed. Thus, an electric current pulse in a conductor linking the magnetic material may have an amplitude which is sufficient to switch the direction of magnetic flux where the magnetic material is stressed, but which is insufficient to switch flux where the magnetic material is unstressed.

Moreover, the stressing of a magnetic material induces an electrical sense signal in a conductor linking the magnetic material. The polarity of the sense signal corresponds with the direction of flux in the magnetic material and is indicative of the storage of a "1" or a "0" information bit. The reading stored information is non-destructive because the magnetic flux returns to its original condition.

In an array of memory elements where the memory elements consist of magnetic material linked by an electrical conductor, an individual memory element may be accessed by a sonic stress wave passed successively through the memory elements. When writing information into a selected memory element, a current pulse is applied to the electrical conductor in time coincidence with the arrival at the memory element of a stress wave.

In constructing transducers for translating an electrical pulse into a stress wave pulse which travels along a row of memory elements with low attenuation, it is found to be difficult to create a stress wave pulse having both a desired intensity and a desired short duration. The stress wave pulse has an undesirably long duration. Stated another way, the time interval between the passage past a point in the material of the leading and trailing edges of the stress pulse is undesirably long. The stress wave pulse spans a corresponding long physical distance in the direction of its propagation. Heretofore, memory elements were appropriately separated so that only one at a time was affected by the stress wave. The result is that known stress wave magnetic memories are unduly large in physical dimensions and are correspondingly slow in operation.

It is an object of the invention to provide an improved sonic stress wave memory having a relatively high density of individual magnetic memory elements.

It is another object to provide an improved sonic stress wave memory wherein a considerable number of individual memory elements are simultaneously stressed at any given instant and are individually accessed by means of an equal number of respective electrical conductors.

It is yet another object to provide an improved memory system capable of the simultaneous storage and retrieval of a number of bit-serial information signals, or, stated another way, the storage and retrieval of word-serial information signals in which each word contains many bits.

It is a further object to provide an improved memory construction including thin magnetic films deposited on a substrate through which an accessing sonic stress wave is propagated.

According to an example of the invention, there is provided a row of magnetic memory elements and means

2

to propagate a sonic stress wave through the row of memory elements, the elements being closely spaced so that a plurality of elements are stressed at any instant by the stress wave. The individual magnetic memory elements may be constituted by a thin film spot of magnetic material deposited on a substrate providing a good conductor for a sonic stress wave. Individual electrical conductors link respective memory elements capable of being stressed at any one instant. Each electrical conductor also links other non-adjacent memory elements which are sufficiently spaced from each other so that only one is stressed at a time. When writing, bit-serial information signals are applied to respective electrical conductors in time-position synchronism with a sonic stress wave passed through the row of memory element. When reading, a stress wave applied through the row of memory elements results in the inducing of bit-serial information signals on each of the electrical conductors. The reading process does not destroy the stored information. The arrangement described may be extended to include a plurality of rows of magnetic elements.

According to another example of the invention, each stress wave is a burst of stress waves. The individual cycles of the stress wave burst are spaced apart a distance equal to the distance between successive individual magnetic memory elements.

In the drawings:

FIG. 1 is a diagram of an array of magnetic memory elements and electronic means for selectively accessing the memory elements;

FIG. 2 is a time chart which will be referred to in explaining the operation of the system of FIG 1;

FIG. 3 is a diagram illustrating a different physical construction, using thin magnetic film memory elements, which may be employed in the system of FIG 1; and

FIG. 4 is a diagram illustrating a stress wave memory employing a burst of stress waves having cycles related to the spacing of the magnetic memory elements.

Referring now in greater detail to FIG. 1, there is shown a magnetic magnetostrictive member or rod R_1 made of material such as permalloy. A row of magnetic memory elements $B_1, B_2, B_3, B_1', \dots, B_3''$ is constituted along the rod R_1 by the magnetic material and by electrical conductors C_1, C_2 and C_3 linking the magnetic material at equally spaced intervals along the rod R_1 . A transducer 10 is provided at one end of the magnetostrictive rod R_1 for the purpose of generating a sonic stress wave pulse which propagates through the rod R_1 to the opposite end where it is absorbed without reflection by a mechanical damping termination 12 . The transducer 10 may be a piezoelectric crystal which, in response to an electrical pulse applied to its terminals, generates a longitudinal mode sonic stress wave. Other known transducers and stress wave modes may be employed.

The individual memory elements B_1 through B_3'' along the rod R_1 are closely spaced in relation to the distance between the leading and trailing edges of a sonic stress wave propagated through the magnetostrictive rod. The transducer 10 and the rod R_1 are designed to produce a sonic stress wave pulse which has a required amplitude and which has a given minimum practical dimension between its leading and trailing edges in the direction of propagation through the rod R_1 . The minimum practical extent or span of a sonic stress wave is undesirably large in relation to the desired close space of magnetic elements along the rod.

The desired close spacing of magnetic elements is accomplished by employing a conductor C_1 linking non-adjacent memory elements B_1, B_1' and B_1'' , a conductor C_2 linking non-adjacent elements B_2, B_2' and B_2'' , and a conductor C_3 linking non-adjacent memory elements $B_3,$

B_3' and B_3'' . Adjacent memory elements B_1 , B_2 and B_3 fall within the dimension spanned by the leading and trailing edges of a sonic stress wave and may all be stressed at a given instant of time. However, these memory elements are linked by individual electrical conductors C_1 , C_2 and C_3 through which individual information signals may be written into or read out of the respective memory elements when they are all simultaneously stressed. The number of consecutive memory elements B_1 , B_2 and B_3 , and the corresponding number of individual conductors C_1 , C_2 and C_3 is selected to be substantially equal to and not more than the number of memory elements spanned by a stress wave pulse.

Additional magnetostrictive rods R_2 , R_3 and R_4 are similarly provided with a transducer 10 at one end and a termination 12 at the other end. The conductors C_1 , C_2 and C_3 linking memory elements B_1 through B_3'' on magnetostrictive rod R_1 also link corresponding memory elements on all of the magnetostrictive rods R_2 , R_3 and R_4 . Only one of the four transducers 10 shown is electrically energized at one time from a row selection circuit 20. The row selection circuit 20 is supplied with a start pulse over a line 22 from a timer 24. The timer 24 also supplies timing signals over lines 26 to a write-sense switch 30 which directs the timing signals over write output lines 32 or over sense output lines 34. The write output lines 32 are connected to respective write pulse generators W_1 , W_2 and W_3 having outputs connected to respective conductors C_1 , C_2 and C_3 . The write drivers W_1 , W_2 and W_3 are also receptive to individual sources I_1 , I_2 and I_3 of bit-serial input information.

The timing pulse outputs on lines 34 from the write-sense switch 30 are connected to respective sense amplifiers S_1 , S_2 and S_3 . The sense amplifiers are also receptive to signals induced on the respective conductors C_1 , C_2 and C_3 . The sense amplifiers S_1 , S_2 and S_3 are shown as connected to opposite ends of the same conductors C_1 , C_2 and C_3 as the respective write pulse generators W_1 , W_2 and W_3 . It is to be understood that the conductors C_1 , C_2 and C_3 should be provided with suitable terminations, as is conventional, to minimize reflections and permit the conductors to be used for both reading and writing purposes. Alternatively, each of the conductors C_1 , C_2 and C_3 may be constituted by two separate conductors, one of which is connected to a sense amplifier and the other of which is connected to a write pulse generator.

The operation of the system of FIG. 1 will now be described with references to the timing chart of FIG. 2. A write cycle is initiated by energizing the timer 24 to supply a start pulse 40 (FIG. 2) over line 22 to the row selector circuit 20. The row selector circuit 20 directs the start pulse to one of the transducers 10. It will be assumed that the transducer 10 at the end of the magnetostrictive rod R_1 receives the start pulse. The start pulse applied to the transducer 10 causes the generation of a sonic stress wave which propagates down the length of the magnetostrictive rod R_1 at the speed of sound through the medium. The duration of the sonic stress wave is assumed to be as represented at 42 in FIG. 2 and to be such that the stress wave spans not more than three adjacent ones of the memory elements B_1 through B_3'' at any given instant of time.

The timer 24 supplies timing pulse waves T_1 , T_2 and T_3 (FIG. 2) through the write-sense switch 30 to respective write pulse generators W_1 , W_2 and W_3 . The write drivers, when activated by the timing pulses, respond to the information signals from the sources I_1 , I_2 and I_3 to appropriately energize the conductors C_1 , C_2 and C_3 in accordance with the "1" and "0" information from the sources. The amplitudes of the information signals supplied to the conductors C_1 , C_2 and C_3 are sufficient to change the magnetic states of the memory elements B_1 through B_3'' solely when the memory elements are stressed by the propagated sonic stress wave. The sonic stress wave causes a temporary reduction in the magnetizing

force needed to change the magnetic state of the material from a condition representing the storage of a "1" or a condition representing the storage of a "0."

When the stress wave is at the position represented at 42 in FIG. 2, the memory element B_1 is stressed and receptive to a write signal occurring at the time t_1 . The write signal applied through conductor C_1 linking memory elements B_1 , B_1' and B_1'' is effective solely on the memory element B_1 because only element B_1 is stressed at this time.

As the stress wave propagates down the row of memory elements, the timing pulse t_1' energizes the conductor C_1 at a time when solely the memory element B_1' of the group B_1 , B_1' and B_1'' is stressed. In this way, the writing of bit serial information from information source I_1 is accomplished in memory elements B_1 , B_1' and B_1'' at the times of pulses t_1 , t_1' and t_1'' during the propagation of a sonic stress wave along the row of memory elements. The writing of information from source I_2 in time-interlaced fashion at the times of pulses t_2 , t_2' and t_2'' is accomplished during the same propagation cycle of the sonic pulse wave. Likewise, during the same propagation of the sonic stress wave, information is written from source I_3 into memory elements B_3 , B_3' and B_3'' at the times of pulses t_3 , t_3' and t_3'' .

In the nondestructive reading of stored information, a start pulse is applied from timer 24 through the row selector circuit 20 to the transducer 10 of a selected one of the magnetostrictive rods. The resulting stress wave is propagated along the selected rod and it causes the inducing of sense signals on the conductors at each memory element in the row. The sense signals have a polarity indicative of whether the memory element was storing a "1" or a "0" information bit. The inducing of electrical sense signals in response to the passage through the magnetic material of a stress wave results from a well-known physical phenomenon called the Villari effect. The stress wave momentarily changes the number of flux lines linking the electrical conductor and thus induces a sense signal in the conductor. After the stress wave passes, the magnetic material returns to its previous condition indicative of the storage of a "1" or "0."

The timing pulse waves t_1 , t_2 and t_3 from the timer 24 are directed through the write-sense switch 30 to the sense amplifiers S_1 , S_2 and S_3 . The timing pulses strobe or energize the sense amplifiers to sequentially respond to the bit-serial sense signals induced on each of the conductors C_1 , C_2 and C_3 . The application of timing pulses to the sense amplifiers is not absolutely necessary because the sense signals reach the respective sense amplifiers in orderly time sequence determined by the propagation of the sonic stress wave. However, it is desirable to have the sense amplifiers inactive or disabled during the writing of information into the memory.

The system illustrated in FIG. 1 including rows of magnetostrictive magnetic memory elements through which a sonic pulse wave is propagated may also be constructed using rows of thin magnetic film spots on a sonic conductor as illustrated in FIG. 3. In FIG. 3, a substrate 50, which may be glass, is provided with a row of thin magnetic film spots 52 which cooperate with conductors C_1 , C_2 and C_3 to form a row of magnetic memory elements B_1 through B_3'' . The conductors are connected to write amplifiers and sense amplifiers after the manner illustrated in FIG. 1. The sonic substrate 50 is provided at one end with a sonic transducer 54 electrically energized from an electrical pulse generator 56. The opposite end of the sonic substrate 50 is physically terminated at 58 to prevent undesired sonic reflections.

Each individual thin magnetic film spot 52 is preferably deposited to have an anisotropic easy axis 60 in a direction angularly related to the corresponding electrical conductor and the direction of propagation of the sonic stress wave from the transducer 54.

In the operation of the arrangement of FIG. 3, a sonic

stress wave propagated along the row of thin magnetic film spots 52 causes a stressing of the magnetic material which tends to make the easy axis rotate to a direction aligned with the direction of particle motion inherent in the stress wave. The rotation of flux resulting from the rotation of the easy axis causes the inducing of a sense signal on the corresponding electrical conductor. The polarity of the induced sense signal depends on whether the thin magnetic film spot was magnetized in one direction or another along its easy axis. The two directions correspond with the storage of a "1" or a "0" information bit. The direction of flux along the easy axis 60 is determined when writing information by the polarity of the current pulse supplied through the corresponding conductor from the respective write pulse generator W.

The single row of thin magnetic film memory elements shown in FIG. 3 may be employed as a single unit, or may be employed as one of many rows of magnetic elements in a system like that of FIG. 1. The operation of the memory system of FIG. 3 is generally similar to the operation described in connection with the system of FIG. 1. Writing is accomplished by propagating a sonic stress wave along the row of memory elements and coupling bitserial information signals to the conductors in time-position synchronism with the movement of the stress wave. Reading is accomplished by propagating a stress wave along the row of memory elements and sensing the information signals that are successively induced on the electrical conductors.

FIG. 4 shows a stress wave magnetic memory similar to the one shown in FIG. 3 but differing therefrom in that a pulse generator 56' is provided which energizes a transducer 54' to generate a burst of sonic stress waves, rather than a single stress wave pulse. The burst of stress waves is propagated through the row of magnetic memory elements B₁ through B₃'. Three successive instantaneous positions of the propagated burst of stress waves are represented at t, t' and t''. The frequency of the individual waves or cycles in the burst of stress waves is selected so that the distance between successive individual waves is equal to the spacing between the magnetic memory elements of the group including B₁, B₂ and B₃. The spacing of the waves is also equal to the spacing of the magnetic memory elements in the group B₁', B₂', B₃' and the group B₁'', B₂'', B₃''. The space between the last magnetic element of one group and the first magnetic element of the following group may be greater than the space between elements of one group, as shown. The spacing may be selected to minimize the possibility of the effective stressing at one instant of time of memory elements in more than one group. In the operation of the memory of FIG. 4, information is recorded in the magnetic memory elements B₁, B₂ and B₃ at the instant when the propagated burst of stress waves reaches the position t. At this time, the three memory elements are simultaneously stressed in the direction represented by the positive peaks 60 of the burst shown at t. At this time instant, the write drivers W₁, W₂ and W₃ are simultaneously energized to cause a switching of the three stressed magnetic memory elements to directions indicative of corresponding "1" and "0" information signals. The current flowing in conductor C₁ from the write driver W₁ does not affect the memory element B₁' in the following group because the element B₁' is stressed in the wrong direction to permit a change in the magnetic flux. This is illustrated by the negative polarity of the stress at 62. Element B₂' is not affected because no stress is applied to it.

At a following instant of time, the propagated burst of stress waves reaches the position represented at t'. At this instant, the write drivers W₁, W₂ and W₃ energize the conductors C₁, C₂ and C₃ to record information in the memory elements B₁', B₂' and B₃' in the second group of memory elements. Similary, at a following instant of time when the propagated burst of stress waves reaches position t'', information is recorded in memory

elements of the third group. It is therefore seen that write drivers W₁, W₂ and W₃ each supply bit-serial information signals which are successively recorded in the three groups of magnetic memory elements.

When it is desired to reproduced the information stored in the memory of FIG. 4, a burst of stress waves is again generated in the transducer 54' and propagated through the row of magnetic memory elements. At the three instants when the propagated burst passes through the positions represented at t, t' and t'' information signals are induced on the conductors C₁, C₂ and C₃ and are sensed by the sense amplifiers S₁, S₂ and S₃. The sense amplifiers simultaneously provide outputs corresponding with the information stored in memory elements B₁, B₂ and B₃ of the first group, then supply output signals corresponding with the information stored in the second group, and finally supply output signals corresponding with information stored in elements of the third group. All of the amplifiers are strobed at the times t, t', t'' so that they provide outputs only at the desired instants of time.

The use, as illustrated in FIG. 4, of a burst of stress waves is advantageous because the generation and propagation of a burst of stress waves is more easily and effectively accomplished than the generation and propagation of a narrow single stress wave. The higher frequency of the cycles of a burst of stress waves is characterized in being propagated over a given distance with less attenuation than a lower frequency stress wave. The burst of stress waves also produces peaks of stress having a desired higher amplitude than can conveniently be provided using a single stress wave. A further advantage results from the arrangement wherein the peaks of the cycles of a stress burst are related to the spacing of the individual magnetic memory elements. All of the memory elements of a group can be simultaneously stressed for the reading and writing of information. The memory elements B₁, B₂ and B₃ of the first group may be used for the storage of one word having bits all of which are accessed in parallel. Each of the second and third groups of memory elements provides storage space for successively accessed different words.

The use of three conductors C₁, C₂ and C₃ in the arrangements of FIGS. 1, 2 and 3 is purely illustrative. The number of conductors is determined by the number of closely spaced memory elements which are spanned by a sonic wave pulse having a minimum practical duration. The systems described overcome the space and operating speed limitations imposed by the dimension in the direction of propagation of a sonic wave pulse, and permit the efficient and effective storage of a large number of information bits in a given physical space.

What is claimed is:

1. The combination of
a group of magnetic elements,
means to propagate a sonic stress wave through said
group of magnetic elements, said magnetic elements
being closely spaced so that said sonic stress wave
spans a plurality of magnetic elements, and
a number of conductors substantially equal to and not
more than the number of magnetic elements spanned
by a sonic stress wave, each of said conductors linking
a plurality of magnetic elements which are
sufficiently spaced from each other so that only one
is stressed at a time.
2. A memory array comprising
a group of thin magnetic film memory elements,
means to propagate a sonic stress wave through said
group of memory elements, said memory elements
being closely spaced so that said sonic stress wave
spans a plurality of memory elements, and
plurality of conductors each linking a plurality of
non-adjacent memory elements which are sufficiently
spaced from each other so that only one is stressed
at a time.

3. A memory array comprising
a row of magnetic memory elements,
means to propagate a sonic stress wave through said
row of memory elements, said memory elements being
closely spaced so that said sonic stress wave spans a 5
plurality of memory elements,
a plurality of conductors each linking a plurality of non-
adjacent memory elements which are sufficiently
spaced from each other so that only one is stressed
at a time, 10
means to energize each of said conductors with bit-serial
information signals occurring in time-position syn-
chronism with a sonic stress wave passing through
memory elements linked by the conductor, and
a plurality of sense means each coupled to one of said 15
conductors to receive stored information in the form
of bit-serial information signals induced on the
conductor in response to the propagation of a sonic
stress wave through the row of memory elements.
4. A memory array comprising 20
a row of magnetic memory elements,
means to propagate a sonic stress wave through said
row of memory elements, said memory elements
being closely spaced so that said sonic stress wave
spans a plurality of memory elements, 25
a number of conductors substantially equal to and not
greater than the number of memory elements spanned
by a sonic stress wave, each of said conductors linking
a plurality of non-adjacent memory elements
which are sufficiently spaced from each other so that 30
only one is stressed at a time,
means to energize each of said conductors with bit-
serial information signals occurring in time-position
synchronism with a sonic stress wave passing through
memory elements linked by the conductor, and 35
a plurality of sense amplifiers each coupled to one of
said conductors to receive stored information in the
form of bit-serial information signals induced on the
conductor in response to the propagation of a sonic
stress wave through the row of memory elements. 40
5. The combination of
a plurality of rows of magnetic memory elements,
means to propagate a sonic stress wave through any
selected one of said rows of memory elements, said
memory elements in each row being closely spaced 45
so that said sonic stress wave spans a plurality of
memory elements, and
a plurality of conductors each linking a plurality of
memory elements in one row which are sufficiently
spaced from each other so that only one memory 50
element in the row is stressed at a time, each con-
ductor also linking corresponding memory elements
of all other rows.
6. A memory array comprising
a plurality of rows of magnetic memory elements, 55
means to propagate a sonic stress wave through any
selected one of said rows of memory elements, said
memory elements in each row being closely spaced
so that said sonic stress wave spans a plurality of
memory elements,
- 60
a plurality of conductors each linking a plurality of
memory elements in one row which are sufficiently
spaced from each other so that only one memory
element in the row is stressed at a time, each con-
ductor also linking corresponding memory elements 65
of all other rows,
- means to energize each of said conductors with bit-
serial information signals occurring in time-position
synchronism with a sonic stress wave passing through
memory elements linked by the conductor along 70
any selected one of said rows, and
a plurality of sense amplifiers each coupled to one of
said conductors to receive stored information in the
form of bit-serial information signals induced on the
conductor in response to the propagation of a sonic 75

- stress wave through any selected one of the rows of
memory elements.
7. A memory array comprising
a plurality of rows of magnetic memory elements,
means to propagate a sonic stress wave through any
selected one of said rows of memory elements, said
memory elements in each row being closely spaced
so that said sonic stress wave spans a plurality of
memory elements,
a number of conductors substantially equal to and not
greater than the number of memory elements spanned
by a sonic stress wave, each of said conductors linking
a plurality of non-adjacent memory elements in
one row which are sufficiently spaced from each
other so that only one memory element in the row is
stressed at a time, each conductor also linking corre-
sponding memory elements of all other rows,
means to energize each of said conductors with bit-
serial information signals occurring in time-position
synchronism with a sonic stress wave passing through
memory elements linked by the conductor along any
selected one of said rows, and
a plurality of sense amplifiers each coupled to one of
said conductors to receive stored information in the
form of bit-serial information signals induced on the
conductor in response to the propagation of a sonic
stress wave through any selected one of the rows of
memory elements.
8. A memory array comprising
a plurality of rows of thin film magnetic memory
elements,
means to propagate a sonic stress wave through any
selected one of said rows of memory elements, said
memory elements in each row being closely spaced so
that said sonic stress wave spans a plurality of mem-
ory elements,
a number of electrical conductors substantially equal to
or less than the number of memory elements spanned
by a sonic stress wave, each of said conductors linking
a plurality of nonadjacent memory elements in
one row which are sufficiently spaced from each other
so that only one memory element in the row is
stressed at a time, each conductor also linking corre-
sponding memory elements of all other rows,
means to energize each of said electrical conductors
with bit-serial information signals occurring in time-
position synchronism with a sonic stress wave pass-
ing through memory elements linked by the conductor
along any selected one of said rows, whereby in-
formation is stored in the memory elements, and
a plurality of sense amplifiers each coupled to one of
said electrical conductors to receive stored informa-
tion in the form of bit-serial information signals
induced on the electrical conductor in response to the
propagation of a sonic stress wave through any se-
lected one of the rows of memory elements.
9. A stress wave memory comprising
a group of magnetic elements,
means to propagate a burst of sonic stress waves
through said group of magnetic elements, said burst
of stress waves having a number of cycles spaced to
simultaneously stress a corresponding number of
magnetic elements, and
conductors linking said magnetic elements for the re-
cording and reproducing of digital information.
10. A stress wave memory comprising
a group of magnetic memory elements,
means to propagate a burst of sonic stress waves
through said group of magnetic memory elements,
said burst of stress waves having a distance between
cycles equal to the distance between successive mag-
netic memory elements, and
conductors linking respective magnetic memory
elements.

11. The combination of
a row of magnetic elements,
means to propagate a burst of sonic stress waves
through said row of magnetic elements, said magnetic
elements being closely spaced so that said burst of
sonic stress waves spans a plurality of magnetic
elements, and
a number of conductors substantially equal to the num- 5
ber of magnetic elements spanned by a burst of sonic
stress waves, each of said conductors linking a plu- 10
rality of magnetic elements which are sufficiently
spaced from each other so that only one is stressed
at a time.
12. A memory array comprising
a row of magnetic memory elements, 15
means to propagate a burst of sonic stress waves
through said row of memory elements, said memory
elements being apart a distance equal to the distance
between cycles of said burst, and
a plurality of conductors each linking a plurality of 20
non-adjacent memory elements which are sufficiently
spaced from each other so that only one is effectively
stressed at a time.
13. A memory array comprising
a row of magnetic memory elements arranged in suc- 25
cessive groups,
means to propagate a burst of sonic stress waves
through said row of memory elements, said memory

elements of each group being spaced apart a distance
equal to the distance between cycles of said burst,
said burst spanning the memory elements of one
group,
a plurality of conductors each linking one memory ele-
ment of each group,
means to energize each of said conductors with bit-
serial information signals occurring in time-position
synchronization with a sonic stress wave passing through
memory elements linked by the conductor, and
a plurality of sense means each coupled to one of said
conductors to receive stored information in the form
of bit-serial information signals induced on the con-
ductor in response to the propagation of a sonic stress
wave through the row of memory elements.
